UNITED STATES PATENT OFFICE

2,499,063

ILLUMINATED SIGN APPARATUS

Hy C. Hammer, Chicago, Ill., assignor to Hammer Brothers, Incorporated, Chicago, Ill.

Application December 10, 1947, Serial No. 790,740

4 Claims. (Cl. 40—130)

1

This invention relates to illuminated sign apparatus and the like.

An object of the invention is to provide a novel means for illuminating a sign whereby the indicia upon the sign are made to stand out with a glowing or accentuated appearance. Yet another object is to provide a simple sign structure wherein light from a cold cathode tube or other luminous tube is employed for edge illumination of transparent plates, the plates being so designed with respect to color and translucency as to produce a novel effect in the illumination of the indicia of the sign. Yet another object is to provide novel frame structure wherein the sign parts are brought together and maintained in a novel and effective arrangement. Other specific objects and advantages will appear as the specification proceeds.

The invention is illustrated, in a preferred embodiment, by the accompanying drawing, in which—

Figure 1 is a front view in elevation of sign apparatus embodying my invention; Fig. 2, a broken rear view in elevation; Fig. 3, an enlarged transverse sectional view, the section being taken as indicated at line 3—3 of Fig. 2; and Fig. 4, an enlarged sectional view, the section being taken as indicated at line 4—4 of Fig. 2.

In the illustration given, 10 designates a metal strip formed in the shape of a tube with the end 11 overlapping the end 12. In the tubular casing thus provided, I secure at spaced intervals suspension brackets 13 formed of plastic or other suitable material. If desired, a rubber or other resilient body may be employed to form a portion of the bracket.

In the illustration given, the bracket 13 is held in place by the metal screw parts 14. The inner end of the bracket is provided with laterally-extending arms 15 which receive a flexible element 16 for confining a luminous tube 17 against the member 15. At one corner of the sign, I provide an angular terminal socket 18 receiving both ends of the luminous tube 17. The member 18 may be provided with an electrode at one end of the tube and an electrode at the other end of the tube whereby electrons may be emitted from the firing point of one electrode and pass through the tube to the other electrode, the tube, of course, being provided with the usual means for increasing the luminosity thereof. Instead of the cold cathode tube illustrated, it will be understood that any other suitable type of tube or source of light may be employed.

In the structure illustrated, I provide a bracket 55 sults. The introduction of light through all four

support 19 carried by the wall 10 on the inner side thereof and receiving the edges of the plates 20 and 21. The bracket 19 carries a metal frame 22 provided on its inner side with a resilient rim 23 of rubber or other suitable material for supporting at spaced intervals the plates 20 and 21. The spaced supports 22 firmly hold the plates 20 and 21 in the relation shown in Figs. 3 and 4, with the main edge portions of the plates 20 and 21 exposed to the light from the luminous tube 17. With this arrangement, the light emitted from the tube 17 passes directly through the edges of the plates 20 and 21.

The plates 20 and 21 are preferably formed of materials having a different rate of transmission of light. For example, I prefer that plate 20 be formed of a dark colored material or a differently colored material from the color of plate 21. Plate 21 may be formed of colored glass or plastic or of other relatively transparent material. In the illustration given, I provide a back plate 20 formed of dark amber and a front plate 21, for example, formed of colored glass. Upon the back of the glass plate 21, I form the letters 24 spelling out the word "sign." It will be understood that any indicia, either in the form of lettering or figures, etc., may be employed.

Operation

30 In the operation of the sign, electric current is admitted to the electrode at one end of the tube and electrons passing from such electrode to the opposite electrode bring about the illumination of the tube throughout its length. Light 35 passes inwardly through the edges of the plates 20 and 21 and bring about an unusual lighting effect around the lettering 24. I have found that the employment of a differently colored back plate 20 gives a glowing or accentuating edge effect about the lettering which makes the lettering stand out with unusual brilliance. Such effect is not produced by an ordinary glass upon which the lettering is formed and which is edge illuminated. By employing a front transparent 40 sheet and a rear translucent or colored sheet, lettering or decorative material being placed between the sheets, the effect of light passing through the two sheets of material from the edges thereof creates unusual effects about the 45 indicia, giving coloring or glowing effects which seem to project the indicia forward in relief. By having the luminous tube enclose the entire plates, the effects just described are uniform in character and produce no distortion in the re- 50 sults. The introduction of light through all four

sides of the plates seems to produce a cumulative effect, building up the edge colors about the indicia.

The sign structure is extremely simple, with a tubular frame serving as a housing for the light tube and also as a means for supporting the plates in edge relation thereto.

While I have shown certain specific details as illustrating one mode of employment of the invention, it will be understood that such details may be modified widely by those skilled in the art without departing from the spirit of my invention.

I claim:

1. In illuminated sign apparatus, a frame, a light source extending about the frame, a plurality of plates of contrasting colors and carried in said frame with their edges exposed to said light source, and indicia carried between said plates.

2. In illuminated sign apparatus, a frame, a perimetric light source extending around the frame, a plurality of plates differing in color and carried in said frame with their edges exposed to said light source, and indicia carried between said plates, the rearmost of said plates being dark colored and the foremost of said plates being clear.

3. In illuminated sign apparatus, a frame providing a continuous tubular border, a luminous tube housed within said tubular border, at least two light-permeable plates carried in said tu-

bular border with their edges exposed on all sides to the light from said luminous tube, and indicia carried by said forward plate, said rear plate being dark colored and said front plate being clear.

5. In illuminated sign apparatus, a tubular frame, a cold cathode tube extending through said frame, means for illuminating said tube, a plurality of light-permeable plates carried in said frame with their edges exposed to said light tube, 10 means on said frame for supporting at spaced intervals said plates thereon, at least the rear plate being of a color different from that of the transparent front plate, and indicia between said plates.

15 HY C. HAMMER.
